(57) **CLAIM**

We claim the ornamental design for a lighting device, as shown and described.

DESCRIPTION

FIG. 1 is a front perspective view of a lighting device, showing our new design;

FIG. 2 is a right side view thereof;

FIG. 3 is a bottom plan view thereof;

FIG. 4 is a left side view thereof;

FIG. 5 is a top plan view thereof;

FIG. 6 is a front view thereof;

FIG. 7 is a rear view thereof; and

FIG. 8 is left side view of a lighting device showing a second embodiment of our new design without a clipping device wherein the design of the second embodiment has the same appearance as the first embodiment without the clip detail.

FIG. 9 is a front perspective view of a lighting device, showing a third embodiment of our new design;

FIG. 10 is a right side view of the lighting device thereof; and,

FIG. 11 is a rear view thereof, wherein the bottom view, left side view and front view of the lighting device of FIG. 9 is the same as the views illustrated in FIGS. 3–6 respectively.

The broken line showing is superimposed on the continuous surface of the claimed design, is for illustrative purposes only, and forms no part of the claimed design.
